MANICURE TABLE

Lucille E. Green, Rte. 1, Box 16K, Carlsbad, N. Mex.

Filed Oct. 7, 1960, Ser. No. 62,413

Term of patent 14 years

(Cl. D33—14)

I claim:

The ornamental design for a manicure table, as shown.
